HARRY L. FINK, OF NEW YORK, N. Y.

TERRAZZO STRIP

Application filed June 24, 1929. Serial No. 373,162.

The invention relates to metal strips used to separate sections or areas of different colors or compositions, of walls or floors of plastic material, usually concrete mixtures; 5 or to produce surface "patterns" in such floors, these structures being usually called "terrazzo" or "terrazzo mosaic". The strips are therefore conveniently identified as "terrazzo strips."

10 The general object is to provide an improved strip having a wide upper surface, which produces wide metal zones or stripes separating the tile or mosaic areas, and defining the surface "pattern." These strips as 15 heretofore made are usually of sheet metal of moderate thickness, whose upper edges provide only narrow surface lines or stripes.

A more particular object is to provide the 20 desired wide top surface as a part of an originally separate top or "head" strip, of substantial cross-section, permanently secured to the main or "body" strip of sheet metal, by rivets, and preferably by hollow, or tubular rivets. Thus a substantial economy of material is effected, and the upper 25 portion of the complete strip has ample strength and rigidity. The tubular rivets also provide for a cross-bonding by the plastic material passing therethrough.

30 The top or head strip preferably has a dependent portion or face overlapping and welded to an upper marginal face of the body strip, and a horizontal flange or shoulder abutting the upper edge of the body strip.

35 The characteristics and advantages of the invention are further sufficiently explained in connection with the following detail description of the accompanying drawing, which shows one representative embodiment.

40 After considering this example, skilled persons will understand that many variations may be made without departing from the principles disclosed, and I contemplate the employment of any structures that are properly within the scope of the appended claims.

In the drawing:

Fig. 1 is a combined sectional and perspective view of a terrazzo strip, embodying the invention in one form.

50 Fig. 2 is a section at 2—2, Fig. 1.

Fig. 3 is a section at 3—3, Fig. 1.

The main or body strip 1 is of sheet metal (usually brass) of moderate thickness, as usual. It may have any suitable formations to form a bond with the concrete material, such as the integral bowed strips 2, produced by punching or pressing operations. The upper edges 3 of these strips may in some cases define the upper surface 4 of the lower or base layer 5 of plastic composition, in which the lower part of the body strip 1 is embedded, the upper or finishing layer 6 of one or a variety of compositions or colors being then poured between the partitions provided by the upper portions of the strips.

The upper portion of the complete strip 70 consists of an originally separate strip or bar 7 of substantial cross-section (this being also usually brass). The sectional form of this bar may vary. As shown, it is of nearly oblong cross-section, having one side cut away below the top to form an inset face 8 fitting against the upper margin of strip 1, and a shoulder 9 overlying the upper edge of strip 1.

The top bar has a flat upper face 15 of substantial width, greater than that of the base strip, to provide a relatively wide visible metallic strip or band on the wall or floor surface, when the complete strip is "set" 80 in the plastic structure in the usual way.

The top bar 7 is connected to the strip 16, passing through registering holes bored in the strip and in the depending flange portion of the top bar at suitably spaced intervals, the rivet ends being upset or flanged over as at 17 to permanently connect the two members together and provide ample strength and rigidity. The tubular rivets also provide for cross-bonding by the plastic material flowing through them when the upper layer of the terrazzo is laid.

95 It will be noted that the longitudinal edges of the body strip 1 are straight and uninterrupted. Consequently if desired, the strips 1 may be used as complete terrazzo strips, in cases where only narrow exposed surface lines in the finished floor are wanted. But where wider surface lines are desired, the 100

same stock strips 1 may be employed with the addition of the L-shaped bars 7.

I claim:

1. A terrazzo strip comprising a base strip 5 of sheet metal of moderate thickness and a top bar of relatively thick cross-section having a top surface of substantial width, and a depending portion lying against the upper margin of the strip, the bar and strip being 10 secured together by hollow rivets passing through the strip and said depending portion of the bar.

2. A terrazzo strip comprising a base strip 15 of sheet metal of moderate thickness and a top bar of relatively thick cross-section having a top surface of substantial width, and a depending portion lying against the upper margin of the strip, the bar and strip being 20 secured together by tubular rivets passing through the strip and said depending portion of the bar.

3. A terrazzo strip comprising a base strip 25 of sheet metal of moderate thickness and a top bar of relatively thick cross-section having a top surface of substantial width, and a depending portion lying against the upper margin of the strip, the bar and strip being 30 secured together by tubular rivets passing through the strip and said depending portion of the bar, the ends of the rivets being flanged over to engage the strip and bar faces.

4. A terrazzo strip comprising a base strip 35 of sheet metal of moderate thickness having straight uninterrupted longitudinal edges and pressed-out portions between the edges for anchoring the base strip in cement or the like, and a top bar of relatively thick L-shaped cross-section having a top surface of 40 substantial width and a depending portion lying against the upper margin of the strip, the bar and strip being secured together by tubular rivets passing through the strip and said depending portion of the bar, the ends of the rivets being flanged over to engage the 45 strip and bar faces.

In testimony whereof I affix my signature.
HARRY L. FINK.
